UNITED STATES PATENT OFFICE.

GEORGE E. CHRISTENSEN, OF FULLERTON, NEBRASKA.

INCUBATOR HEATER.

Application filed August 30, 1921. Serial No. 496,838.

To all whom it may concern:

Be it known that I, GEORGE E. CHRISTENSEN, a citizen of the United States, residing at Fullerton, in the county of Nance and 5 State of Nebraska, have invented certain new and useful Improvements in Incubator Heaters, of which the following is a specification.

My invention relates to heating systems 10 for hot-water incubators and more particularly to the boiler unit of the heating system. It chief object is the production of a boiler with the minimum amount of labor and material, and which at the same 15 time has the maximum efficiency in responding to the rapid and sudden fluctuations in temperature found in places where farm incubators are usually operated.

These and other objects will be more 20 specifically referred to in the accompanying description, and in connection with the drawings forming a part of this application, of which drawings,

Figure 1 shows the preferred form of my 25 heater installed on an incubator, the incubator being shown diagrammatically and in outline, and with parts broken away to more clearly disclose the boiler and its heating connections.

Figure 2 illustrates one modification of 30 my boiler, showing one method of constructing the boiler so that the exit and return pipes will be at approximately the same level on the wall of the incubator.

Figure 3 shows a vertical section of the 35 boiler, and clearly discloses the inner partition walls, as well as the proportion of the parts.

In the figures, numeral 10 refers to the incubator itself. The incubator is mounted on 40 legs or pegs 11 to set it above the level of the floor or other support. Access to the interior of the incubator is obtained by means of the door 12 arranged to swing on hinges 13. All of this however is common to nearly 45 all incubators, and is illustrated here merely for the purpose of showing how my heating system is applied to the incubator.

The boiler is indicated generally by the 50 reference numeral 14. The boiler has two parallel side walls 15, an end wall 16, and a partial top wall 17. A vertical partition wall 18 extends downwardly between the parallel side walls from the inner extremity of the top wall 17. The lower end of the 55 vertical wall 18 is connected to the outer extremity of the top wall 17 by means of

an upwardly and rearwardly inclined wall 19. The walls 17, 18, and 19 are secured to the side walls 15 in water-tight relation, as for example by soldering, but any other 60 known method as welding, would accomplish the same purpose. The result of this construction is a water container having a flue 20 positioned vertically at one end, and having an inclined heating surface 19. 65

In the construction of the boiler, only two pieces of rectangular sheet metal are used, and these pieces are each bent at only two places. The side walls 15 and the end wall 16 are formed by twice bending such a sheet 70 of metal, as can readily be seen from an inspection of the drawings. The top and partition walls are likewise formed from a single sheet of metal, which is cut to a predetermined length and of a width equal to 75 that of the end wall, and when bent will form a right triangular enclosure. In my preferred construction I make the walls 17 and 18 of approximately equal lengths, but the inclination of the wall 19 may be varied 80 by varying the proportions of the lengths of the walls 17 and 18.

The water reservoir of the boiler is provided with a filling tube 21 in the upper wall and preferably near the upper end of 85 the inclined wall. A cap or stopper 22 of any approved form closes the mouth of the filling tube to protect the contents of the reservoir from dust and other extraneous matter which might interfere with the 90 operation of the heater. On the side of the boiler next to the incubator are two apertures 23 and 24. Aperture 23 is near the top of the water level in the reservoir and preferably near the outer end of the inclined 95 wall 19. Aperture 24 is placed at or near the lowest point of the reservoir.

Pipes are connected with the apertures to circulate the water for heating the incubator. In the construction shown in Figure 1, pipe 25 is connected to the reservoir at the aperture 23 and serves to carry the hot water from the surface and into the egg chamber of the incubator. The pipe as shown lies parallel to one of the sides of the incubator, and its end is connected to pipe 26 which is parallel to the side of the incubator opposite the boiler. The pipe 26 is in turn connected to the pipe 27 which is parallel to the third side of the incubator. As shown, the three pipes 25, 26, and 27 lie 100 in a substantially horizontal plane, but they may if desired, be given an inclination 110

throughout. In Figure 1, the pipe 27 is shown connected to a pipe 28 which is parallel to the side of the incubator adjacent to the boiler but inclined downwardly to the level of the aperture 24. I have shown the aperture 24 as somewhat smaller in diameter than the aperture 23, and in the construction shown, the pipe 28 is reduced from the diameter of the larger aperture to the diameter of the smaller aperture. The pipe 28 is connected to a short pipe 29 which passes out through the wall of the incubator and into the reservoir through the aperture 24.

For heating the water a lamp 30 is positioned directly beneath the flue of the boiler. The lamp is mounted on an oil tank 31 from which it is fed, and the oil tank is filled through an opening which is normally kept closed by a cap 32. The lamp is provided with a chimney 33 which hinges on the lamp base at 34. The arrangement gives sufficient clearance for lowering the chimney when it is desired to trim and clean the wick.

Directly above the boiler flue is a shutter 35 or valve 35 connected to a horizontal rod 36 through the link or chain 37. The rod 36 is connected with any desired type of thermostat on the interior of the incubator. The connections between the rod 36 and the thermostat may be made either through the top or the side of the incubator. Since however neither the character nor the position of the thermostat constitutes a part of my invention, I do not desire to cumber the record with descriptions of old and well known structures. It will readily be seen however that when the shutter 35 is raised, the heated air from the lamp will pass upward through the boiler flue without appreciably heating the water in the boiler, but when the shutter closes the outlet of the boiler flue, the heated air is deflected and passes underneath the heating wall 19 of the boiler. The function of the thermostat is to raise or lower the shutter 35 as the temperature of the incubator gets above or below the normal.

It is sometimes desirable to arrange all of the pipes of the heating system to lie in one plane. In Figure 2 I have shown a modification of the boiler which permits of such an arrangement. In this construction the boiler itself is made exactly as before described, but the lower aperture serving to return the water to the boiler on its circuit is enclosed in a box-like structure 38 extending to or near the top of the boiler. The box 38 is provided on its outer side with an aperture 39 at or near the level of the aperture 23. It will readily be seen that in assembling the heating system, the return pipe can be made to approach the boiler at the same level as that of the exit pipe, or if it is desired to set the entire piping system at a slight incline, the aperture 39 may be positioned slightly below the level of the aper-

ture 23. I have illustrated the box structure 38 merely to show one method of connecting the piping system to the boiler, but it is apparent that a number of other arrangements would also accomplish the same purpose. For example, if the pipes 28 and 29 were kept in the plane of the pipes 25 and 26, another pipe could be jointed to and dropped from the end of the pipe 29 to the aperture 24, this extra length of pipe being mounted perpendicularly and between the boiler and the adjacent wall of the incubator. Still another way of doing this is to cut the aperture 24 at a higher level and to connect it with a downwardly extending pipe on the interior of the boiler, the pipe being open at its lower end. In this case the return will be inside the boiler.

As before said, the boiler is of the simplest possible construction. The sheet metal is cut into two predetermined sizes, each rectangular in form. Each piece is bent in only two places. The equipment for cutting the strips, for bending them, for punching the holes, and for uniting the pieces in watertight relation is all found in every tin shop, and the entire operation is so simple that it can be performed with the minimum amount of unskilled labor.

The heating surface 19 is inclined and is relatively large in size. The heated air is held in contact with the heating surface 19 by the two wings of the sides 15 which prevent lateral dissipation of the heated air and confines the current to a narrow passage. This confined current against the large heating surface 19 not only utilizes the maximum amount of heat from the lamp but causes an almost instant response to the most sensitive thermostat. This is for the reason that when the flue 20 is fully open the surface 19 becomes a positive cooling surface, being freely in contact with the cooler air of the room. The surface 18 is in no sense a cooling surface because it is always in contact with more or less heated air, nor does it serve as a heating surface because it is vertical and thereby allows the heated air to pass over it without appreciably affecting its temperature. The water heaters at present in use have horizontal heating surfaces of small area, thus wasting a large amount of the heat, and being more or less confined, these heating surfaces can not function as cooling surfaces to prevent the incubator from overheating.

I have had this heater in use on my incubator for two successive seasons. I have constructed a number of them for trial purposes. I have found that they are not only easily made and installed, but they result in a positive saving of fuel and of attention over all others which I have tried. I have found that the heating surface is so effective that it requires only a short time after clos-

ing the valve on the flue 20, to bring the water in the reservoir to a boiling temperature.

While I have described the heater in connection with its use on an incubator, and although I intend to use it chiefly on incubators, I do not desire to relinquish any rights to the heater when used for other purposes. It could be made to serve as a heater for the artificially heated hot bed, and other uses may develop later, and I wish it to be understood that I reserve to myself the right to put the heater to any use which it may be found to serve.

Having thus described my invention, what I claim and desire to protect by Letters Patent of the United States is:—

1. A boiler comprising a pair of sheet metal strips, one of said strips being relatively wide and bent U-shape, the other strip being narrow and bent into triangular shape and being of a width substantially equal to the space between the side portions of the first strip and secured therebetween to provide a boiler enclosure between the two folded and assembled strips.

2. A boiler comprising a pair of sheet metal strips, one strip being relatively wide and the other strip being relatively narrow, the wide strip being U-shape to provide a pair of side walls and a connecting end wall,

the narrow strip being bent around to bring its opposite ends together and provide an enclosure therein, said narrow strip being of a width substantially equal to the spacing apart of said side walls and secured therebetween to provide a boiler enclosure, said narrow strip being spaced from the said end wall to provide between the latter and the side walls and the narrow strip a flue extending along one edge of the boiler.

3. An incubator boiler consisting of an end wall and spaced side walls, said end and side walls being integral, an integral right-angled element secured to said side walls in the space therebetween, one of the legs of the element being parallel to and spaced from the end wall, the other leg partially closing the space between the upper edges of the spaced side walls, the angled element and the side walls together constituting a closed water receptacle, the vertical space enclosed by the side walls, the end wall and the perpendicular leg of the angled element therefore a flue for the passage of heated air, and the open space bounded by the side walls and the hypotenuse of the angled element being a by-pass for the passage of the heated air.

In testimony whereof I affix my signature.

GEORGE E. CHRISTENSEN.
